UNITED STATES PATENT OFFICE.

ARTHUR H. BALL, OF BUFFALO, NEW YORK.

FENCE.

Substitute and continuation of application Serial No. 412,425, filed September 24, 1920. This application filed August 30, 1926. Serial No. 132,648.

This invention relates to a fence post to which woven wire or other fencing may be readily applied or from which said fencing may be readily removed.

5 This application is a substitute and continuation of former application Ser. No. 412,425, filed Sept. 24, 1920.

One of the objects of this invention is to provide improved means for expeditiously 10 and readily securing a fence wire to or removing the same from a post made of any suitable material.

Another object of this invention is to provide a construction which is applicable 15 to fence posts made of a plastic material such as concrete, and to which the fencing may be clamped very tightly, so that, if any one portion of the fence between any certain fence posts is broken or loosened, the 20 remaining portion thereof is not affected deleteriously.

A further object of this invention is to provide means for quick and convenient replacement of any portion of the fencing or 25 the tightening thereof. Further objects and advantages will appear more clearly in the following description and accompanying drawings, wherein:

Figure 1 is a front elevation of one form 30 of improved fence post and showing a portion of wire fencing applied thereto.

Figure 2 is a vertical longitudinal section through the same taken on line 2—2, Figs. 1 and 3.

Figure 3 is an enlarged horizontal section 35 through the said fence post, taken on line 3—3, Fig. 2.

Figure 4 is an enlarged fragmentary vertical section through one corner of the fence 40 post, taken on line 4—4, Fig. 3.

Figure 5 is an enlarged perspective view 45 of the horizontal forming ring of the fence post.

Figure 6 is an enlarged fragmentary perspective view of the vertical wedging plate.

Figures 7 and 8 are enlarged fragmentary perspective views of modified forms of vertical wedging plates.

Figure 9 is an enlarged perspective view 50 of a modified form of forming ring.

Similar characters of reference refer to like parts throughout the several views.

The numeral 10 represents a vertical post 55 which may be constructed of any suitable material but in this instance is constructed

as a concrete pillar which is preferably of the shape shown in the drawings, being that of a frustrated, square pyramid. The lower wider portion of said pillar is adapted to be sunk a sufficient depth below the surface 60 of the ground 11, while the upper end of the same is adapted to carry any suitable fencing such as the wire fencing 12 which is illustrated. In the main body of the concrete pillar 10 and parallel to the inclined, 65 square corners thereof are four inclined forming bars 13, which reinforce the pillar in a manner common to the reinforced concrete art. During the process of forming the concrete pillar 10 by means of pouring 70 the plastic cement material into a suitable mold, these longitudinal forming bars are held in properly spaced relationship (relatively to each other and to the mold) by means of a plurality of forming rings 14 75 which are disposed transversely relatively to said forming bars and are disposed at approximately equal intervals along the length thereof. The proper locationing of these forming rings 14 relatively to the forming 80 bars 13 is accomplished in the following manner:

As best shown in Fig. 5, each corner of each of said forming rings 14 is provided with a pair of locating notches 15 one of 85 which extends a short distance downwardly from the upper face of each corner of said ring while a companion notch extends a short distance upwardly, from the lower face of each corner of said ring. Formed at suitable longitudinal intervals in each of the aforementioned forming bars 13 is a loop shaped portion or eye 16, inwardly of which is formed a constricted portion or stricture 17 constituted of the neck of said eye 16. 90 Before assembling the forming rods and the forming rings and prior, of course, to pouring the cement into the mold to form the pillar 10, the eyes 16 and strictures 17 of the forming bars are comparatively large as 95 shown by dotted lines in Fig. 4. That is, the vertical bore or inner diameter of each eye 16 is somewhat greater in size than the vertical width of the main body of each forming ring 14 while the vertical opening 100 of the stricture 17 is somewhat less than the vertical distance between any companion pair of upper and lower notches 15. On one side of each forming ring 14 is formed an opening 18. By means of this opening each 105

of the forming bars 13 may be passed in succession through the said vertical opening 18 and then the main body of said ring 14 is passed or threaded through the eyes 16 of the forming bars. These forming bars are then moved horizontally around said forming ring until one of said forming bars is located at each of the corners of said ring, the eyes 16 of said forming bars dropping 10 down into the notches 15 of said forming ring. The eyes 16 of the forming bars are however prevented from disengaging from the forming rings by reason of the fact that the stricture 17 is smaller than the vertical 15 distances between the locating notches 15. After the forming rings and the forming bars have thus been placed in proper position each of the eyes 16 of each bar is pressed together manually by means of a heavy 20 pincers or other suitable tool until the same is firmly locked into the notches 15 of each ring and until the opposite vertical inner faces of each stricture 17 come into contact with each other, as shown in full lines in 25 Figs. 4 and 5. By this operation, all of the forming rings 14 and the forming bars 13 are suitably clamped in proper position relatively to each other. This combined structure of united forming bars and rings forms 30 the backbone of the fence post, the concrete or other plastic material being poured over the same in a suitable mold in the usual and well known manner.

Connected integrally to one side of each 35 of the forming rings 14 is a reduced neck 20 which extends horizontally and laterally out some distance beyond the outer face of the pillar 10. Formed integrally at the outer end of said neck is a clamping head 21, which 40 projects or extends horizontally and laterally outwardly from each side of said neck 20. Adapted to be arranged against the front face of the pillar 10, is a wedging plate 22, which is provided with a plurality of 45 horizontal slits or enlarged apertures 23 which are adapted to be passed over the aforesaid clamping heads 21. Extending vertically upwardly from the central part of each of these elongated apertures 23 is a 50 longitudinal slot 24, which (as in the case of the elongated aperture 23) extends entirely through the wedging plate from the front to the rear face thereof. After the wedging plate 22 has been moved rearwardly 55 against the pillar 10 and the elongated aperture 23 has been moved over the clamping head 21, the said clamping plate is then dropped vertically downwardly, the reduced neck 20 being received by the said longitudinal slot 24. For the purpose of causing the 60 wedging plate to be forced firmly against the face of the pillar 10, each of the vertical longitudinal slots 24 is flanked on either side by a wedging shoulder 27, which, as shown in Fig. 6 may be formed integrally with the

main portion of the wedging plate 22 by suitably stamping the same so as to form the said wedging shoulders 27, the latter having front inclined or beveled faces which are inclined downwardly and inwardly, the lower 70 termini of which are substantially flush with the outer flat face of the main body of the wedging plate 22. These inclined wedging shoulders are adapted to bear against the inner faces of the clamping heads 21, so that, 75 as the clamping plate is driven down by a mallet or otherwise forcibly moved vertically downwardly relatively to the pillar 10, said plate is caused to be forcibly jammed back against the face of said pillar 10. Inasmuch as the aforesaid fencing 12 is adapted to be placed in position between the front face of the pillar 10 and the rear face of the 80 said wedging plate 22, it follows that said fencing is frictionally held very firmly and 85 rigidly in position against the post so that when any particular portion of the fencing around a field becomes fractured, only the portion between two certain fence posts is 90 affected, all the rest of the fence remaining 95 taut and securely in place by reason of the fact that the fencing is clamped rigidly to each and every fence post individually and cannot be moved horizontally relatively to any one of said fence posts, as is the case 100 with ordinary removable fencing. To remove the fencing from any particular fence post, it is merely necessary to drive the wedging plate 22 vertically upwardly after which said plate and also the fencing may 105 be completely removed.

A section of a modified form of wedging plate is shown in Fig. 7. In this case, inclined faces or wedging shoulders 270 are formed by crimping a wedging plate 220, the longitudinal slot 240 and the enlarged aperture 230 being substantially the same as in the construction previously described.

By this construction a certain amount of resiliency is obtained between the said wedging plate 220 and the clamping head 21 with which it is adapted to engage, the metal bending at the crimped portion 30. This resilient construction is adapted to compensate for a faultily constructed cement pillar which has the clamping heads 21 arranged at irregular distances from the face of said pillar. In such case, the particular pair of wedging shoulders 270 which is engaging with the underside of the particular clamping head that is closest to the pillar, will be bent inwardly or resiliently forced toward the pillar. This will allow the other wedging shoulders or inclined faces 270 to come into contact with their companion clamping heads and thereby allow the latter to press the fencing back firmly and equally against the pillar along the entire length thereof. A similar object is also attained by the modified construction of 125

wedging plate which is illustrated in Fig. 8, wherein is shown a pair of modified wedging shoulders or inclined faces 127 which are formed by slitting and bending the main body of the wedging plate 122 to form a resilient, upwardly and outwardly extending elastic tongue or wing 32. Centrally said tongue is provided with the usual longitudinal slot 124 which is adapted to receive the neck 20 of the companion forming ring 14, while the front face of the elastic tongue is adapted to bear against the inner face of the companion clamping head 21 as in the other constructions of wedging plate. It will be noticed that the upper end of the slot 124 stops short of the upper end of the tongue so that there is no liability of the clamping head overriding the said tongue. A modified form of retaining ring 34 and modified forming bars 33 are shown in Fig. 9. In this case said forming bars 33 are constructed of flat bar stock, the eyes 16 and the stricture 17 of the construction of Figs. 4 and 5 being eliminated. Furthermore, the retaining rings 34 are unprovided with the notches 15 and the opening 18 of the construction of Figs. 3 and 5. The said straight metal bar stock or forming bars 33 of Fig. 9 are merely wired, in the usual and well known manner, to the square corners of the said modified retaining rings 34 and thus retained in place relatively to each other until the cement has been poured around them.

It will be evident that a large number of absolutely uniform cement fence posts may be quickly and expeditiously made, if fabricated in accordance with the present invention. The forming rings not only give the proper shape to the forming rods, but lock the same together in proper position as well. In addition to this, the forming rings act as exceedingly firm and permanent anchors for the clamping heads 21. Furthermore, the clamping plate may be easily applied to or removed from the cement pillar 10 so as to make very convenient the placing in position or the removal or repair of the fencing 12. Furthermore, the fencing when clamped in place, is prevented from shifting in any direction whatsoever relatively to each and every fence post to which it is attached. The resilient wedging shoulders 270 and 127 enable the fence post to function properly despite very faulty workmanship, maintaining at all times a uniform pressure against the fencing 12, throughout the entire width thereof. Furthermore, the metal work is of such simple form as to enable a manufacturer to send only the said metal work to a farmer, who can easily and successfully make and set up the fence posts and the fencing himself, certain chaplets, etc. being supplied, of course, by the manufacturer, that are not shown in the draw-

ings. It is quite well understood in the art, that cement work is easy to mold whenever the iron frame work is of substantially the same shape and proportion as the finished piece of work, as is the case in the present invention. 70

Although some of the features of this invention are more particularly suited for use in connection with a fence post which is made of concrete other features are equally applicable to posts made of metal or other materials and it is therefore to be understood that this invention is not limited except by the terms of the following claims. 75

I claim:

1. A fence comprising a post, a support having a neck projecting laterally from the post and an enlarged head arranged at the outer end of said neck, and a clamping plate between the inner side of which and the outer side of the post a fence wire is adapted to be clamped and which is provided with a slot having a narrow longitudinal portion adapted to receive said neck, and a wide part at one end of said longitudinal portion and adapted to be traversed by said head and said plate being provided on opposite sides of the longitudinal portions of said slot with inclined faces which are adapted to engage with the inner side of 90 said head and produce a wedging effect for pressing the fence wire against said post. 95

2. A fence comprising a post, a support having a horizontal ring embedded in said post, a horizontal neck projecting laterally from said ring to the exterior of the post and an enlarged head at the outer end of said neck, and a clamping plate between the inner side of which and the outer side of the post a fence wire is adapted to be clamped and which is provided with a slot having a narrow longitudinal portion adapted to receive said neck and a wide part at one end of said longitudinal portion and adapted to be traversed by said head and said plate being provided on opposite sides of the longitudinal portions of said slot with inclined faces which are adapted to engage with the inner side of said head and produce a wedging effect for pressing the fence wire against 100 said post. 105

3. A fence comprising a post, a support having a neck projecting laterally from the post and an enlarged head arranged at the outer end of said head, and a clamping plate between the inner side of which and the outer side of the post a fence wire is adapted to be clamped and which is provided with a slot having a narrow longitudinal portion adapted to receive said neck and a wide part at one end of said longitudinal portion and adapted to be traversed by said head and said plate being provided on opposite sides of the longitudinal portions of said slot with inclined faces which are adapted to engage 110 115 120 125 130

with the inner side of said head and produce a wedging effect for pressing the fence wire against said post, the longitudinal portion of said slot and said inclined faces being formed on a wing which is stamped out of the stock of said plate and is attached thereto at the base of said inclined faces and detached therefrom at the brow of said inclines so that said wing is resilient and engages 10 yieldingly with said head.

4. A fence comprising a concrete post, a support having a horizontal ring embedded in said post, a horizontal neck projecting laterally from said ring to the exterior of 15 the post and an enlarged head at the outer end of said neck, longitudinal rods embedded in said post and engaging with the inner

side of said ring, and a clamping plate between the inner side of which and the outer side of the post a fence wire is adapted to 20 be clamped and which is provided with a slot having a narrow longitudinal portion adapted to receive said neck, and a wide part at one end of said longitudinal portion and adapted to be traversed by said head and 25 said plate being provided on opposite sides of the longitudinal portions of said slot with inclined faces which are adapted to engage with the inner side of said head and produce a wedging effect for pressing the fence wire 30 against said post.

In testimony whereof I hereby affix my signature.

ARTHUR H. BALL.
